UNITED STATES PATENT OFFICE.

FREDERIC SCHAEFER, OF PITTSBURGH, PENNSYLVANIA.

BRAKE-ROD JAW.

1,259,676.

Specification of Letters Patent. Patented Mar. 19, 1918.

Application filed August 19, 1916. Serial No. 115,789.

To all whom it may concern:

Be it known that I, FREDERIC SCHAEFER, a resident of Pittsburgh, in the county of Allegheny and State of Pennsylvania, have 5 invented a new and useful Improvement in Brake-Rod Jaws, of which the following is a specification.

This invention relates to improvements in brake rod jaws.

- 10 One of the objects of the invention is to provide an improved brake rod jaw which can be readily formed by forging and hence be made much stronger than similar jaws made of cast metal.
- 15 Another object is to provide an improved jaw in which a minimum amount of metal is used which is so disposed that the jaw will withstand all service stresses without danger of deformation or breakage.

- 20 Another object is to provide an improved brake rod jaw which can be readily formed in proper shape without requiring difficult and expensive manufacturing operations.

The accompanying drawings illustrate an 25 embodiment of the invention. The views of said drawings are as follows:—

Figure 1 is a top plan view of the brake rod jaw with one of the jaw members thereof shown in cross section.

- 30 Fig. 2 is a side elevation and partial cross section of the jaw shown in Fig. 1.

Fig. 3 is a bottom plan view of the brake rod jaw.

Fig. 4 is an end view.

- 35 Fig. 5 is a cross section on the line 5—5 of Fig. 2.

Fig. 6 is a cross section on the line 6—6 of Fig. 2.

The jaw is formed from a single piece of 40 metal, preferably a rolled plate of rectangular outline, although if desired the plate may be sheared to approximately the form of the blank out of which the jaw is made. This metal plate is then subjected to the action of suitably formed dies which trim out 45 the plate and properly shape it. The dies trim out the plate so as to form two side members 1 and 2 which are joined by an upwardly bowed portion 3 at one end and a downwardly bowed portion 4 intermediate the ends. The side members or wings 1 and 2 are bent downwardly by the dies so as to dispose them side by side and substantially parallel to each other with the two connect-

ing portions 3 and 4 located as shown in Fig. 2 so that there is an opening therebetween, as at 5, through which the end of the brake rod 6 may pass. Figs. 4 and 5 illustrate the position of the side members before they are bent downwardly by the dies to their final position.

In the die operation the excess metal from the portions which are cut away is caused in part to flow into the blank so as to form thickened portions at certain points in order to give maximum strength with a minimum amount of material. For example, the metal around the openings 7 in the eyes 8 at the ends of the side portions is thickened, as at 9. The edges of the blank are also turned down to form flanges 10 for strengthening the jaw.

The brake rod 6 is connected to the jaw by heating its end and passing it through the opening 5 until it projects entirely beyond the forward end of the jaw and it is then bent into hooked form and moved backwardly until the hook end 11 engages the downwardly bowed portion 4 of the jaw. The end of the rod is then bent around the 75 bowed portion 4 until it engages the body portion of the rod, as illustrated in Fig. 2. The brake rod thus grips the bowed portion and is prevented from moving longitudinally in the jaw.

In order to hold the brake rod more firmly in position, the jaw is provided with integral projections 12 and 13 which, in effect, form extensions of the upwardly bowed portion 3 and are arranged to be bent around 90 the end 11 of the brake rod. These projections or extensions are formed parallel to each other on the jaw, as shown in dotted lines in Fig. 4. After the brake rod is positioned in the jaw, they are bent around 95 the end 11 of the rod, as shown in Fig. 4, to hold it in position. The projections are shaped so that they overlap in the manner shown in Fig. 3, which allows them to be bent around the brake rod and firmly grasp 100 it without requiring that they be of exact size and shape so as to match each other and form a joint. This construction is very practical because it is difficult to form the projections so that they will meet each other 105 and allow a proper opening for the rod, the expansion and contraction of the metal and variations in sizes of the rods serving to

make it difficult to have the projections meet to form a joint. The projections overlapping in approximately the same plane—transversely—on the rod, increases the locking strength.

Any tendency of the brake rod to straighten out under severe tension strains is resisted by the bent-over portions 12 and 13 which clasp the end of the rod. The metal is sufficiently rigid to offer a very material resistance to any straightening out tendency of the hook and no weld at the edges of the extensions is necessary because the tendency to spread apart these members is very slight and is amply taken care of by the stiffness of the metal.

The structure of the brake jaw is such that it can be readily formed by die forging, thereby making it possible to utilize wrought metal with its inherent tensile strength. The jaw is not only lighter but it is also much stronger than ordinary cast jaws. It is made from a single piece of metal by die operations which are relatively simple so that the jaw can be inexpensively manufactured.

It is to be understood that the structure shown is for purposes of illustration only and that other structures may be devised which come within the spirit and scope of the appended claims.

What is claimed is:—

1. A forged brake rod jaw composed of wrought metal and comprising jaw members lying side by side and connected by an upwardly bowed portion and a downwardly bowed portion, said latter portion serving as a means for engaging a hooked brake rod and permitting the end of the rod to be bent into engagement with the rod body, and means on the jaw capable of being readily bent around the end of the rod to hold it in position.

2. A forged brake rod jaw composed of wrought metal and comprising jaw members lying side by side and connected by an upwardly bowed portion and a downwardly bowed portion, said latter portion serving as a means for engaging a hooked brake rod end and permitting the end of the rod to be bent in a plane parallel to the plane of the side members into engagement with the rod body, and means on the jaw for preventing displacement of the hooked end of the brake rod.

3. A forged brake rod jaw composed of wrought metal and comprising jaw members lying side by side and connected by an upwardly bowed portion and a downwardly bowed portion, said latter portion serving as a means for engaging a hooked brake rod end and permitting the end of the rod to be bent into engagement with the rod body, and means integral with the jaw for pre-

venting displacement of the hooked end of the brake rod.

4. A forged brake rod jaw composed of wrought metal and comprising jaw members lying side by side and connected by an upwardly bowed portion and a downwardly bowed portion, said latter portion serving as a means for engaging a hooked brake rod end and permitting the end of the brake rod to be bent into engagement with the rod body, and ears extending from the jaw for clasping the bent end of the rod.

5. A forged brake rod jaw composed of wrought metal and comprising jaw members lying side by side and connected by an upwardly bowed portion at one end and a downwardly bowed portion intermediate the ends, said latter portion serving as a means for engaging a hooked brake rod end, and ears on the end of the jaw having the upwardly bowed portion arranged to be bent into engagement with the end of the brake rod to hold the rod in position.

6. A forged brake rod jaw composed of wrought metal and comprising jaw members lying side by side and connected by an upwardly bowed portion and a downwardly bowed portion, said latter portion serving as a means for engaging a hooked brake rod end and permitting the end of the brake rod to be bent into engagement with the rod body, and ears extending from the jaw having their ends cut at an angle so that they may be readily bent to an overlapping position around the brake rod.

7. A forged brake rod jaw composed of a single piece of wrought metal and comprising side members spaced apart in substantially parallel relation and joined by an upwardly bowed portion at one end and a downwardly bowed portion adjacent said end whereby an opening is formed for receiving a brake rod, said downwardly bowed portion serving as a means for engaging the hooked end of a brake rod and permitting the end of said rod to be bent into engagement with the rod body, and projections extending from the side members at their ends which are joined by the upwardly bowed portion adapted to be bent around the end of the brake rod to hold it in position.

8. A forged brake rod jaw composed of a single piece of wrought metal and comprising side members spaced apart in substantially parallel relation and joined by an upwardly bowed portion at one end and a downwardly bowed portion adjacent said ends, whereby an opening is formed for receiving a brake rod, said downwardly bowed portion serving as a means for engaging the hooked end of the brake rod and permitting the end of said rod to be bent into engagement with the rod body, and projections extending from the side members at their ends which

are joined by the upwardly bowed portion and capable of being bent around the end of the brake rod for holding it in position, the ends of said projections being cut at an angle so that they may be readily bent to overlap on the rod without overlapping each other.

In testimony whereof, I have hereunto set my hand.

FREDERIC SCHAEFER.
